UNITED STATES PATENT OFFICE.

JOHN R. NICKOLS, OF KNOXVILLE, IOWA.

CAR-COUPING.

SPECIFICATION forming part of Letters Patent No. 244,650, dated July 19, 1881.

Application filed May 12, 1881. (Model.)

To all whom it may concern:

Be it known that I, JOHN R. NICKOLS, of Knoxville, in the county of Marion, and in the State of Iowa, have invented certain new and useful Improvements in Car-Couplings; and I do hereby declare that the following is a full, clear, and exact description thereof, reference being had to the accompanying drawings, and to the letters of reference marked thereon, making a part of this specification.

This invention relates to certain improvements in car-couplers; and it has for its object to provide a device whereby the coupling-links may be manipulated without necessitating the entrance of the operative between the cars, and the danger consequent thereupon obviated, as more fully hereinafter specified. This object I attain by the apparatus and devices illustrated in the accompanying drawings, in which—

Figure 1 represents a perspective view of one end of a car, showing my improved coupling device; and Fig. 2, detached detail views of such device.

The letter A indicates the platform of the car, which may be of the ordinary description; and B, the draw-head, which may be constructed with one or more recesses, C, for the coupling-links, and with corresponding apertures, D, for the coupling-pins.

The letter E indicates a curved hanger secured to the edge of the platform by means of staples F or other suitable fastening devices. The said hanger at its lower or free end is provided with a beveled shoulder, G, and rectangular shank H, and with a screw-threaded extension, I.

The letter K indicates a curved bar, which is slotted, as indicated by the letter L, the said slotted portion setting over the rectangular shank of the curved hanger, the bar resting on the beveled shoulder thereof.

M indicates a beveled nut, by means of which the bar K is confined to the hanger. The outer end of the bar K is provided with a handle, N, by which it may be operated, and near the other end with a notch or recess, P, to receive and hold the coupling-link and direct it to or remove it from the draw-head. The said notch is so constructed as to hold either a bent or straight coupling-link, as may be desired.

The letter R indicates a shoulder on the bar K, which sets against the hanger when the bar is not in use and holds said bar in position out of the way.

Having thus fully described my invention, what I claim, and desire to secure by Letters Patent, is—

In combination with the draw-head B, provided with a series of recesses, C, and apertures D, the bar K, slotted as described, and provided with a notch, P, and shoulder R, the bent hanger E, provided with a beveled shoulder, G, and the nut M, all arranged to operate substantially as specified.

In testimony whereof I affix my signature, in presence of two witnesses, this 25th day of April, 1881.

JOHN R. NICKOLS.
